PUMP JACK

Frederick A. Lage, Gladbrook, Iowa

Application February 23, 1940, Serial No. 320,464

3 Claims.

(Cl. 74—41)

This invention relates to an improvement in pump jacks.

The object of my invention is to provide a simple, durable and inexpensive pump jack adapted to be supported in an oil-tight casing, wherein the mechanism may be operated in an oil or grease bath so as to insure at all times proper lubrication.

A further object is to provide an improved pump jack so constructed and arranged that power may be applied to the lift rod of the pump in such a manner as to cause the lift rod to travel in a straight perpendicular line and within its guides with a minimum amount of lateral movement, whereby the guides for the lift rod may be relieved of excessive wear.

A further object of my invention is to provide in a pump jack an improved speed reducing gear mechanism wherein the noise is greatly reduced.

A further object of my invention is to provide in a pump jack, improved mechanism wherein the power transmitted from a shaft rotating at a continuous and uniform speed may be transmitted to the reciprocating lift rod in uniform accelerated speeds.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a vertical longitudinal sectional view of the casing showing therein in side elevation my improved speed reducing and power-transmitting mechanism, and the manner in which the device is applied to the lift rod of a pump;

Figure 2 is a plan view of the same with the cover removed;

Figure 3 is a detail sectional view taken on the line 3—3 of Figure 1; and

Figure 4 illustrates a modified form of my device.

In the drawing I have used the reference numeral 10 to indicate a pump of ordinary construction having at its top end a bracket 11, which is also of ordinary construction, provided with a guide device 12 in which is slidably mounted the vertically arranged lift rod 13.

My improved jack comprises a frame or casing 14, having a bottom 15, ends 16, and side members 17, a cover 18 being provided for the said casing. Rotatably mounted in the side members 17 is a drive shaft 19 having one end projecting through one of the side members on which is

mounted a belt pulley 20. The central portion of the shaft 19 is provided with a sprocket pinion 21. Rotatably mounted in the opposite end of the side members 17 is a rock shaft 22 having both of its ends extending through the members 17, each of said ends being provided with a lever arm 23 mounted substantially in a horizontal position and having their free ends terminating opposite the vertical center of the pump 10. Connected to the outer end of each of the members 23 is a lift bar 24, said lift bars being on opposite sides of the pump, having their upper ends connected to the lift rod 13 by means of a bolt 25, in such a manner that as the shaft 22 is rocked, the bars 24 will be elevated and lowered, causing the lift rod 13 to be elevated and lowered.

For rocking the shaft 22 I have fixed to said shaft lever arms 26 which extend upwardly and outwardly from said shaft 22, the free ends of 20 the arms 26 being provided with a shaft 27 on which is mounted eccentrically a sprocket wheel 28, said sprocket wheel having a hub 29 of considerable diameter, said hub being arranged concentrically with the circumference of said sprocket, the shaft 27 passing through the hub 29 in a manner clearly illustrated in Figure 1. A chain 30 is passed over the sprockets 21 and 28. From this arrangement it will be seen that the weight of the pump rod 13 will tend to move the outer ends of the arms 22 downwardly and the outer ends of the arms 26 upwardly or away from the shaft 19, so that the chain 30 is always maintained under tensile strain.

From the above it will be seen that if the shaft 35 19 is rotated, then the sprocket 21 will be rotated, and with it the sprocket wheel 28, which will rotate about the shaft 27 as an axis; and inasmuch as the lifting strain is always against the weight of the rod 13, it will be seen that the 40 outer end of the arms 26 will always tend to move upwardly and away from the shaft 19, causing the outer ends of the arms 26 to be oscillated in the arc a—a, while the center 31 of the hub 29, and the sprocket 28 will swing in the arc b—b, so that the lift rod 13 will be reciprocated at uniform accelerated speeds. Under certain conditions the weight of the rod 13 always tends to move the outer ends of the arms 26 upwardly away from the shaft 19, during one-half revolution of the 45 sprocket 28, while the tension on one run of the chain 30 tends to pull the arm 26 towards the shaft 19 during the other half revolution of said sprocket 28.

If conditions are such that the rod 13 offers resistance on its downward movement, and power

has to be applied to accomplish said downward movement, then it is necessary to provide an arcuate plate 32 to engage the periphery of the hub 29, the center of the arc of said plate being in the center of the shaft 19, the plate 32 then serving as a bearing to prevent inward movement of the hub 29 towards the shaft 19 as power is being transmitted to the sprocket 28 during the downward stroke of the rod 13.

Under ordinary pumping conditions, however, the hub 29 seldom ever touches the said plate 32. It will readily be seen, however, that even if the mechanism disclosed herein for operating the lift rod of a pump might be utilized for producing reciprocal movement to other mechanisms wherein it is required that power be transmitted to the reciprocating element in both directions, in which case the arcuate plate 32 would be necessary or an equivalent therefor.

In Figure 4 I have illustrated a modified form wherein the plate 32 is in the form of a roller designed to operate about the axis 19 as a center, so as to overcome the sliding movement between the hub 29 and the periphery of the said roller or the outer surface of the plate 32. However, it will readily be seen that a roller takes up considerably more space in the casing than would be required with an arcuate plate. For that reason the arcuate plate is preferably used in pump jacks.

Thus, it will be seen I have provided a gear mechanism which is preferably used as a pump jack but which may also be utilized as means of converting a constant rotary movement into a reciprocating movement at uniformly accelerated speeds.

One of the advantages of my device lies in the fact that the arms 23 are of considerable length and have their free ends terminating substantially in a transverse line with the movement of the pump rod, and in view of the fact that the links 24 are of considerable length, substantially very little lateral pressure is applied to that portion of the lift rod extending through the guide 12, thereby eliminating wear on the guide and thereby eliminating the excessive amount of power required to operate the pump.

By providing a chain drive in the speed reduction gear mechanism between the rapidly moving shaft 19 and the rock shaft 22, I have provided means whereby a large percentage of the noise is eliminated over that produced by the use of spur gears used in the ordinary speed reduction of devices of this kind, and at the same time my improved device also provides means whereby uniformly accelerated speeds may be imparted to the reciprocating rod similar to that produced by the crank movement which

is quite commonly used in devices of this kind, and at the same time eliminating the angularity of the lift links 24 which always accompanies said lift links when used in connection with a crank action to produce this result.

I claim as my invention:

1. In a device of the class described, a frame, a drive shaft, a sprocket pinion carried by said shaft, a lever arm of the first class, a sprocket wheel, a hub carried by one side of said sprocket wheel and mounted concentrically of its periphery, means rotatably and eccentrically mounting said sprocket and hub to one end of said lever, a chain operatively connecting said sprockets, arcuate means for engaging the periphery of said hub, having its center in common with the center of said drive shaft, means for connecting the other end of said lever arm to a load offering resistance to the movement of said arm in either direction, whereby uniform rotary movement being imparted to the first sprocket will cause the load to be reciprocated at uniform accelerated speeds.

2. In a pump jack comprising a frame, a rock shaft mounted therein, a pair of radially and horizontally mounted lift arms, a pair of rock arms carried by said rock shaft, a shaft carried by the outer ends of the last said arms, an eccentrically mounted sprocket wheel carried by the last said shaft, a drive shaft, a sprocket pinion on said drive shaft, a chain connecting said sprockets, lift bars carried by the free ends of said lift arms, means connecting the ends of said lift bars to the pump rod whereby the weight of the pump rod tends to swing the sprocket wheel away from the said sprocket pinion, wherein uniform rotary movement being imparted to said sprocket pinion will cause the pump rod to be reciprocated at uniformly accelerated speeds.

3. In a device of the class described, a frame, a drive shaft, a drive pinion carried by said shaft, a lever arm, a driven wheel, a hub carried by one side of said driven wheel and mounted concentrically of its periphery, means rotatably and eccentrically mounting said driven wheel and hub at one end of said lever, flexible means operatively connecting said driving and driven wheels, a wheel engaging the periphery of said hub having its center in common with the center of said drive shaft, and means for connecting the other end of said lever to a load offering resistance to the movement of said arm in either direction, whereby uniform rotary movement being imparted to the first sprocket will cause the load to be reciprocated at uniform accelerated speeds.

FREDERICK A. LAGE.
